Application July 17, 1937, Serial No. 154,268

13 Claims. (Cl. 201—64)

This invention relates to electric resistance heating, and the principal object of the invention is to provide a new and improved heating element and a new and improved method of making the same.

In the drawings accompanying this specification and forming a part of this application, we have shown, for purposes of illustration, several forms which our invention may assume, and in 10 these drawings:

Figures 1, 3, 5, and 7 are longitudinal sectional fragmentary views illustrating steps in the method of producing an electrical resistance heating element in accordance with our invention, Figures 2, 4, 6, and 8 being sections taken on correspondingly numbered lines of Figures 1, 3, 5, and 7 respectively.

Figures 9 and 10 are sectional views illustrating another embodiment of a heating element that may result from our method, Figure 9 being a section taken on the line 9—9 of Figure 10, and Figure 10 being a section taken on the line 10—10 of Figure 9.

Figures 11 and 12 show different forms of resistors, which may be used in the embodiment of Figures 9 and 10.

Figures 13 and 14 are cross sections of still other forms of resistance heating elements produced in accordance with our invention,

Figures 15 and 16 illustrate still another form of heating element produced in accordance with our invention, Figure 15 being a transverse section and Figure 16 being a section taken along the line 16—16 of Figure 15 looking in the direction of the arrows.

Referring first to Figures 1 through 8, the method of producing the electrical resistance heating element here illustrated includes first forming an insulating chamber within a metal sheath, desirably seamless, and one way in which this may be accomplished as illustrated in Figures 1 through 4 is by introducing a mandrel 20 of desired form into a metal sheath 21. The mandrel 20 is here shown as having a portion 22 of square cross sectional outline which fits within the inside wall of the sheath 21, the sheath 21 being here shown as of circular cross section. In the particular instance illustrated the mandrel has an end portion 23 which is cylindrical and fits the inside wall of the sheath 21.

After the mandrel 20 has been introduced into the sheath electrical insulating material 24 (see Figures 3 and 4) of suitable form is introduced, in any suitable way, desirably by extrusion, into 55 the spaces 25 (see Figure 2) left between the

mandrel and the inside wall of the sheath. The material 24 may comprise silica, silicates, aluminum oxides, or any refractory oxide or combination of refractory oxides, or any other suitable refractory material, and the material may be mixed with a chemically unstable refractory oxide to act as a bond on hydration, or mixed with a clay, or with any other suitable binder. For the sake of brevity refractory insulating materials suitable for use in our method may be termed plastoid.

After the plastoid insulating material 24 has been introduced in the spaces 25 between the mandrel 22 and the sheath 21, the mandrel 22 is removed leaving the plastoid insulating material 24 to form an insulating chamber 26, in this instance of square cross sectional outline, as shown in Figure 4, within the sheath. The plastoid insulating material is of course of such character that it is to a desired degree self sustaining as to form, so that the mandrel may be withdrawn leaving the material to form the chamber 26. The cylindrical portion 23 of the mandrel leaves a short end portion of the sheath empty in the illustrated instance, but that is not essential.

In the instance illustrated, there is now introduced within the insulating chamber 26, a resistor 27 which is here shown as a helix formed of resistance wire, and the wire desirably has suitably welded thereto at both of its ends lead-in terminals, one of which, 28, may be seen in Figure 5. The resistor is desirably of such size that it fits slidably into the chamber 26.

After the resistor 27 has been introduced into the insulating chamber 26, a further quantity of plastoid insulating material 29 may be extruded into the insulating chamber 26 and about the resistor 27, so as to fill the chamber and embed the resistor as shown in Figures 7 and 8. However, preferably, the refractory insulating material, 29, which is introduced into the chamber 26 after the resistor 27 has been introduced therein, is of granular, pulverulent, or comminuted form, and of such character that it may be compacted by vibration or in any other suitable way. It will be understood that the material in such form may also be mixed with a suitable binding material. In either case the insulating material 29 may also be termed plastoid, since it has the mechanical characteristics of impressionability and fluency, as of a plastic, when it is introduced into the chamber 26, though it may be compacted to a hard mass.

In case that a space 30 is left at the ends of the sheath 21, this space may serve to receive 55

any suitable form of insulation (not shown) for supporting the conductor 28 or any suitable form of terminal (not shown) to which the conductor 28 may be connected, as shown, for example, in the patent to Wiegand 1,997,844, April 16, 1935. However, those skilled in the art will understand that the details of the terminal construction in any embodiment of our invention will depend upon the shape and form of the heater, and the 10 particular terminal design will depend upon considerations for use or production, and that the terminals may project axially through the end openings of the sheath or through any other suitable opening provided therein. These details, 15 per se, form no part of our invention.

Heating elements of the type herein disclosed are adapted to be pressed externally, or they may be compacted interiorly and exteriorly, and if desired they may be formed in the act of pressing 20 into any suitable desired cross-sectional shape, both for the purpose of increasing the compaction of the insulating material within the sheath and for the purpose of specially forming or shaping the sectional shape of the element, 25 and they may be bent across their longitudinal axes to desired configurations.

It will accordingly be understood that while a heating element such as illustrated in Figures 7 and 8 is utilizable in the form there illustrated, 30 it may be worked into other forms to bring the sheath to a cross sectional outline different from the initial cross sectional outline, and the element bent with respect to the initial longitudinal axis to any suitable and desired shape.

It will be evident that the hereinbefore described method permits the positive location of the resistor within the sheath by means of the preformed insulating chamber.

Another embodiment of a resistance heating element produced in accordance with our invention is illustrated in Figures 9 and 10. The element has a metallic sheath 31, the initial cross sectional outline of which, in this instance, is of oblong rectangular form, and the final form may 40 be the same or different. It will be evident that in this instance two mandrels or a mandrel having two spaced parallel portions (not shown) each corresponding to the portion 22 of the mandrel 20 illustrated in Figures 1 and 2, may be 45 utilized to form two axially extending insulating chambers 34, 35 within the sheath 31, by the introduction of plastoid insulating material 36 in the spaces between the mandrel and the inner wall of the sheath 31, and also between the juxtaposed faces of the mandrel portions to form 50 a dividing wall 37. If desired, this dividing wall 37 may have an end 38 terminating a predetermined distance short of one end of the insulating chambers 34, 35, so that a bent part 39 of a 55 helical resistor 40 may be disposed to cross over from one of the chambers 34, 35, to the other. The resistor 40 may be of the form shown in Figure 11, one of the parts, 41, of the resistor being in the chamber 34 and the other part, 42, of the resistor being in the other chamber, 35. The ends of the helical resistor 40 are thus 60 brought to the same end of the sheath 31, and any suitable terminal means may be provided if desired. It is not essential that the dividing wall 65 37 have its end 38 countersunk, as hereinbefore described.

Figure 12 shows another form of helical resistor, 43, which may be inserted in a pair of chambers, such as the chambers 34, 35, shown 70 in Figures 9 and 10, the cross-over, 44, between

the two parts of the resistor 43 being in this instance straightened out, and this resistor being particularly adapted for use where the division wall 37 is not countersunk.

It will be understood that after the resistor 40 (or 43) is inserted in the two chambers, 34, 35, a further quantity of suitable insulating material 32 is desirably introduced in each chamber, as hereinbefore described in connection with the insulating material 29 introduced in the chamber 10 26 of Figure 4.

In Figure 13 is shown a cross section of another embodiment of a resistance heating element in which an insulating chamber 45 is formed within a metallic sheath 46, the cross sectional outline 15 of the inside wall of the chamber 45, as well as of the sheath 46, being in this instance circular. This insulating chamber 45, is formed in the same way as described in connection with Figures 1 through 4, a mandrel (not shown) of circular 20 cross section being however used. After the insulating chamber 45 has been formed a resistor 47 is introduced into the chamber 45, the resistor 47 being in this instance of helical form fitting in the chamber 45. The resistor 47 may be disposed, before introduction into the chamber 48, on a self-sustaining body of friable refractory insulating material 48, which in this instance may be in the form of a rod or stick of cylindrical form. On the other hand, the rod or stick 48 30 may be introduced within the resistor 47 after the resistor has been introduced into the chamber 45, the size and configuration of the stick being of course made suitable to that end. The resistor 47 may have its ends connected to lead-in conductors disposed at opposite ends of the sheath, such as the lead-in conductors 28 of Figures 5 and 7, or the rod of friable insulating material 48 may be provided with a longitudinally extending hole 49 through which a straight- 35 ened out end portion 50 of the helical resistor 47 may be inserted, so as to bring the ends of the resistor to the same end of the sheath 46. The stick or rod 48 may be composed of refractory insulating material of the same characters 45 as the material 29 but brought to a self-sustaining form as by compaction, or it may be of any other suitable refractory material which is friable.

Desirably a heating element such as described 50 in connection with Figure 13 will be pressed in any suitable way, to any suitable form, so that the friable insulating material 48, and also the insulation forming the insulating chamber 45 will be thoroughly compacted about the resistor 47 55 to take up any voids.

In Figure 14 is shown another embodiment of a resistance heating element, an insulating chamber 51 having an inner wall of square cross sectional outline being first formed in a metallic 60 sheath 52, as described in connection with Figures 1 through 4. Within the insulating chamber 51 is disposed a resistor 53 which may be helical, and within the resistor 53 is a rod or stick of friable insulating material 54, here shown 65 as of generally square cross sectional outline fitting within the resistor 53. The resistor 53 and the stick of friable insulating material 54 may be introduced into the chamber 51 in any of the ways already described in connection with Figure 70 13, and thereafter insulating material 55, of any of the forms described in connection with the insulating material 29 of Figures 7 and 8 is introduced in the spaces between the stick 54 and the inside wall of the insulating chamber 51, so as 75

to embed the resistor. If desired, the stick of friable insulating material 54 may be provided with a longitudinally extending hole 56, here shown as of square cross sectional outline, and 5 a straightened portion 57 of one end of the resistor helix may be disposed through this hole, as described in connection with the resistor portion 50 shown in Figure 13. At the time that the insulating material 55 is introduced, some of the 10 same insulating material may be simultaneously introduced in the space between the resistor portion 57 and the inside walls of the hole 56.

The heating element shown in Figure 14 also 15 may be compacted and worked to any desired form in the manners hereinbefore described.

In Figures 15 and 16 is shown a resistance heating element in which is utilized a resistor 58, comprising a zig-zag ribbon of resistance material. The heating element is here shown as comprising 20 a metallic sheath 59 of generally oblong rectangular cross sectional outline in which is formed an insulating chamber 60 here shown as of elongated cross sectional outline. The length of the cross section of the chamber 60 is long 25 enough to receive the zig-zag resistor 58, and the cross section of the chamber is wider at its central portion than the width of the ribbon constituting the resistor 58. It will be evident that the chamber 60 is so formed that the resistor 58 30 may be readily introduced therein, and the resistor is positively positioned by the narrow ends of the chamber while spaces are left between the wide side walls of the chamber and the resistor. After the insulating chamber 60 is formed within 35 in the sheath 59, in the manner described in connection with Figures 1 to 4, the resistor 58 may be introduced into the chamber, and then refractory insulating material 61 may be introduced in the spaces between the inside wall of 40 the chamber 60 and the resistor 58 in the same way that the insulating material 29 is introduced in the case of the embodiment of Figures 7 and 8. As in the previously described embodiments, a heating element, such as shown in Figures 15 45 and 16, may be suitably worked to compact the insulating material within the sheath about the resistor.

It will be apparent that our method is adapted 50 for the production of resistance heating elements in which the sheath may be any desired initial cross sectional outline, and that if desired the elements may be pressed or otherwise worked so that the final cross sectional outline of the sheath may be substantially different in form from the 55 initial outline or it may be of the same or similar form. And, further, that the resistor may be of any desired or suitable form. Also, the elements may have rectilinear longitudinal axes in their final form, or the elements may be bent or otherwise worked so that in the final form the longitudinal axes are non-rectilinear.

From the foregoing it will be apparent to those skilled in the art that each of the illustrated 60 embodiments of our invention provides a new and improved electrical heating element produced in a new and improved manner, and accordingly, the principal object of our invention is accomplished. On the other hand, it also will be obvious to those skilled in the art that the described and illustrated methods and heating elements may be 65 variously changed and modified, or features thereof, singly or collectively, embodied in other steps or embodiments than those described and illustrated, without departing from the spirit of our invention, or sacrificing all of the advantages 70 thereof, and that accordingly, the disclosure here-

in is illustrative only, and our invention is not limited thereto.

We claim:

1. The method of producing a tubular electric heating element, which comprises: introducing 5 plastoid heat-conducting electrical-insulating material into a tubular metallic sheath, into space between mandrel means and said sheath, and forming, on at least part of the inner surface of said sheath, lining comprising said material in 10 self-sustaining condition and conforming to and in heat-transfer contact with the apposite inner surface of said sheath; and introducing a resistor section in spaced relation to said sheath, spaced from said sheath at least in part by said lining. 15

2. The method of producing a tubular electric heating element, which comprises: introducing plastoid heat-conducting electrical-insulating material into a tubular metallic sheath, into space between mandrel means and said sheath, 20 and forming, on at least part of the inner surface of said sheath, lining comprising said material in self-sustaining condition and conforming to and in heat-transfer contact with the apposite inner surface of said sheath; and introducing a resistor section in spaced relation to said sheath, 25 spaced from said sheath at least in part by said lining, and at least partially embedding said section.

3. The method of producing a tubular electric 30 heating element, which comprises: introducing plastoid heat-conducting electrical-insulating material into a tubular metallic sheath, into space between mandrel means and said sheath, and forming, on at least part of the inner surface 35 of said sheath, lining comprising said material in self-sustaining condition and conforming to and in heat-transfer contact with the apposite inner surface of said sheath; and introducing additional heat-conducting electrical-insulating 40 material, and a resistor section in spaced relation to said sheath, spaced from said sheath at least in part by said lining.

4. The method of producing a tubular electric 45 heating element, which comprises: introducing plastoid heat-conducting electrical-insulating material into a tubular metallic sheath, into space between mandrel means and said sheath, and forming, on at least part of the inner surface 50 of said sheath, lining comprising said material in self-sustaining condition and conforming to and in heat-transfer contact with the apposite inner surface of said sheath; and introducing non-plastoid heat-conducting electrical-insulating 55 material, and a resistor section in spaced relation to said sheath, spaced from said sheath at least in part by said lining.

5. The method of producing a tubular electric 60 heating element, which comprises: introducing plastoid heat-conducting electrical-insulating material into a tubular metallic sheath, into space between mandrel means and said sheath, and forming, on at least part of the inner surface 65 of said sheath, lining comprising said material in self-sustaining condition and conforming to and in heat-transfer contact with the apposite inner surface of said sheath; introducing a resistor section in spaced relation to said sheath, spaced from said sheath at least in part by said lining; and thereafter introducing additional heat-conducting electrical-insulating material. 70

6. The method of producing a tubular electric 75 heating element, which comprises: introducing plastoid heat-conducting electrical-insulating material into a tubular metallic sheath, into space between mandrel means and said sheath,

and forming, on at least part of the inner surface of said sheath, lining comprising said material in self-sustaining condition and conforming to and in heat-transfer contact with the apposite inner 5 surface of said sheath; and introducing additional heat-conducting electrical-insulating material while said lining is in plastoid condition, and a resistor section in spaced relation to said sheath, spaced from said sheath at least in part 10 by said lining.

7. The method of producing a tubular electric heating element, which comprises: introducing plastoid heat-conducting electrical-insulating material into a tubular metallic sheath, into 15 space between mandrel means and said sheath, and forming, on at least part of the inner surface of said sheath, lining comprising said material in self-sustaining condition and conforming to and in heat-transfer contact with the apposite inner 20 surface of said sheath; and introducing a resistor section in spaced relation to said sheath, spaced from said sheath at least in part by said lining, and reducing the element in cross-section over at least part of the longitudinal extent of said 25 resistor section.

8. The method of producing a tubular electric heating element, which comprises: introducing plastoid heat-conducting electrical-insulating material into a tubular metallic sheath, into space 30 between mandrel means and said sheath, and forming, on at least part of the inner surface of said sheath, lining comprising said material in self-sustaining condition and conforming to and in heat-transfer contact with the apposite inner 35 surface of said sheath; and introducing a resistor section in spaced relation to said sheath, spaced from said sheath at least in part by said lining, and reducing the element in cross-section over at least part of the longitudinal extent of said 40 section, and at least partially embedding said resistor section.

9. The method of producing a tubular electric heating element, which comprises: introducing plastoid heat-conducting electrical-insulating material into a tubular metallic sheath, into 45 space between mandrel means and said sheath, and forming, on at least part of the inner surface of said sheath, lining comprising said material in self-sustaining condition and conforming to and in heat-transfer contact with the apposite inner 50 surface of said sheath; and introducing additional heat-conducting electrical-insulating material, and a resistor section in spaced relation to said sheath, spaced from said sheath at least in part by said lining, and reducing the element in cross-section over at least part of the longitudinal extent of said resistor section.

10. The method of producing a tubular electric

heating element, which comprises: introducing plastoid heat-conducting electrical-insulating material into a tubular metallic sheath, into space 5 between mandrel means and said sheath, and forming, on at least part of the inner surface of said sheath, lining comprising said material in self-sustaining condition and conforming to and in heat-transfer contact with the apposite inner surface of said sheath; and introducing additional heat-conducting electrical-insulating material 10 while said lining is in plastoid condition, and a resistor section in spaced relation to said sheath, spaced from said sheath at least in part by said lining, and reducing the element in cross-section over at least part of the longitudinal extent of 15 said resistor section.

11. The method of producing a tubular electric heating element, which comprises: introducing plastoid heat-conducting electrical-insulating material into a tubular metallic sheath, into 20 space between said sheath and mandrel means transversely positioned with respect to said sheath at at least one place intermediate the end portion of said sheath, and forming lining comprising said material, apposite at least part of the 25 inner surface of said sheath; and introducing a resistor section in spaced relation to said sheath, spaced from said sheath at least in part by said lining.

12. The method of producing a tubular electric 30 heating element, which comprises: introducing plastoid heat-conducting electrical-insulating material into a tubular metallic sheath, into space between said sheath and mandrel means transversely positioned with respect to said sheath at 35 least at a plurality of spaced places intermediate the end portions of said sheath, and forming lining comprising said material, apposite at least part of the inner surface of said sheath; and introducing a resistor section in spaced relation to said sheath, spaced from said sheath at least in part by said lining.

13. The method of producing a tubular electric heating element, which comprises: introducing plastoid heat-conducting electrical-insulating 45 material into a tubular metallic sheath, into space between said sheath and mandrel means in effect polygonal in cross-section and transversely positioned with respect to said sheath by abutment of the corners against the inner surface of said sheath, and forming lining comprising said material, apposite at least part of the inner surface of said sheath; and introducing a resistor section in spaced relation to said sheath, spaced from 50 said sheath at least in part by said lining.

JAMES G. LAMPE.
ROBERT J. KING.
